[57] ABSTRACT

A hydraulic directional valve system which may be used for controlling motor cylinders associated with a tractor or the like has paired sliding spool valves operated in opposite directions by a walking beam lever to control connection of an inlet and an outlet with either of a pair of motor ports. Slow rates of feed are obtained by metering the flow out of the motor port, whether induced by pump pressure or gravity. For this purpose, a pilot operated metering-out valve has its pilot controlled by the main spool to provide first a series of gradually increasing small openings and during final movement of the spool to cause instantaneous opening of a large pilot operated metering-out valve which opens in a direction opposite to the movement of the main spool. The system includes a pilot operated pressure relief valve which provides unloading of the supply pressure when all directional valves are in neutral, which provides also hydraulic detent release for the main spool during slow metering and when pressure builds up at the end of a motor stroke and which further provides overload relief at a still higher maximum pressure.

HYDRAULIC CONTROL VALVE

The sliding spool type of directional valve, which is almost universally used in mobile equipment for controlling hydraulic motor cylinders and the like, becomes somewhat unwieldy when designed for the larger systems, and is difficult to control manually for small rates of flow while at the same time providing for a large flow when the valve is in its extreme position. Previous attempts to overcome this problem are typified by U.S. Pat. No. 2,532,552 to Jirsa of Dec. 5, 1950, in which a pair of load-holding poppets move at right angles to the main spool and are opened by cam surfaces provided on the spool to gradually open one poppet or the other. This, however, requires a long stroke for the spool if full opening is to be achieved at extreme displacement and further imposes side loads on the spool which interfere with these operations.

The present invention aims to overcome such problems by the provision of a hydraulic directional valve system comprising a body having a pair of spool-receiving bores, each with a lateral port for inlet and for outlet, with an axial port for flow to and from a motor and with a third lateral port connected by a one-way passage with the axial port, a pair of main spools slideable in the bores to control flow between the lateral ports, operating means to shift the spools simultaneously in opposite directions, a seat in each axial port, a poppet coaxial with each spool and biased toward the seat by a spring and by pressure in the axial port, an oppositely facing smaller seat between each spool and its poppet, and a pilot valve normally closing the smaller seat and arranged to be progressively opened by motion of the main spool for metered flow out of the axial port, and means on the pilot valve for rapidly opening the poppet after a further increment of motion of the main spools.

With directional valves of the closed center type, it is customary to provide an unloading valve controlled by the directional valves to relieve the supply pressure when all directional valves are in neutral. It is also necessary to provide overload protection through provision of a pressure relief valve and a further feature involves a detent for holding a directional valve in extended position and releasing the detent when the motor reaches the end of its stroke or stalls for other reasons. This latter provision requires a pressure sensing valve to release the detent.

The present invention aims to provide all of these functions in a single structure which includes a pilot operated hydraulically balanced pressure relief valve comprising a body having an inlet and an outlet, a poppet valve normally closing flow therebetween and having nearly equal opening and closing areas exposed to inlet pressure, a restricted orifice between the inlet and the closing area, manual means for venting the closing area to the outlet to open the poppet at will independently of the inlet pressure, a pilot relief valve exposed to the closing area and having two stages of opening in the first of which at a predetermined pressure the manual means, if not venting the closing area, is caused to move to a venting position and in the second stage, the poppet acts to limit the inlet pressure to a predetermined higher value.

IN THE DRAWINGS:

FIG. 1 is a view, partly in section taken along line 1-1 of FIG. 3, of a pump and valve assembly incorporating a preferred form of the present invention.

FIG. 2 is a sectional view taken on line 2-2 of FIG. 1.

FIG. 3 is a top view of the pump and valve assembly illustrated in FIG. 1.

FIG. 4 is a fragmentary view on a larger scale illustrating a portion of the structure in FIG. 1.

The pump and valve assembly illustrated in the drawings comprises a main base plate 10 which functions both as a valve body, as a support for a pump 12 (FIG. 15) and as a closing cover for a suitable opening on a gear casing of a tractor or other power device. The pump 12 has a gear 14 which, when the base 10 is secured in place, will mesh with one of the gears inside the gear housing. The pump also carries an inlet filter 20 (FIG. 1) extending downwardly into the gear casing which carries a supply of hydraulic fluid.

Mounted on the base 10 is a directional valve body 18 in which are provided two four-way directional valves 24 and 25, one being controlled by the operating lever or walking beam 20 and the other by a similar lever 22, each of which is pivoted as at 23 to a lug 21 (FIG. 2) on the body 18. Each four-way directional valve, which will hereafter be referred to as valves 24 and 25, consists of a structure such as appears in FIG. 30, where the valve 25 is illustrated. The following description of valve 25 will be equally applicable to the structure of valve 24. Thus, the body 18 is provided with two bores 26 and 28 for valve 25 which receive slideable spools 30 and 32 respectively. The spools 30 and 32 are identical in structure except spool 30 has detent grooves 66 (latter described herein) and spool 32 has a neutral fluid passing groove (also latter described herein). Spool 32 is illustrated with an alternate feature. This piston 55 and spring 57 are provided to allow the lowering of an actuated cylinder only when the pump 12 is operating. This feature will be described at the end of the specification. The operating lever 22 will move both spools in opposite directions away from the neutral position illustrated. Lateral inlet or supply ports 31 communicate with each valve bore as shown in FIG. 1, and are connected by a passage 33 in the base plate 10 with the delivery port of the pump 12. Lateral outlet ports 34 communicate with the sump via the passage 36 in FIG. 1. Secured to the bottom of the valve body 18 (FIGS. 1 and 2) is a terminal block 38 which has a pair of motor ports for each of the directional valves. The ports are shown as ports 40 and 42, in FIG. 2, for valve 25 and one port 42a in FIG. 1 for valve 24. These ports are coaxial with the main valve spools and connect with the bores 26 and 28 through valve seats 44 and 46 respectively. Lateral ports 48 and 50 communicate via passages 52 and 54, containing one-way check valves 56 and 59, with the motor ports 40 and 42. Either the lateral port 48 or the lateral port 50 is connected to the supply ports 31 by the grooves 63 or 65 when the operating lever is moved to direct flow through one of the motor ports 40 and 42. The grooves 63 and 65 may be provided with V-notches 67 to improve the metering at low rates of flow.

Normally closing the seats 44 and 46 are pilot operated meter-out valves 58 and 60 which are controlled by pilot valves 62 and 64 which move with the respective operating levers 20 and 22. The pilot valves 62 and 64 are controlled by the operating levers 20 and 22 through a linkage 68. The linkage 68 is connected to the operating levers 20 and 22 at 70 and 72 respectively and to the pilot valves 62 and 64 at 74 and 76 respectively. The linkage 68 is pivoted at 78 to the body 18. The linkage 68 is provided with a slot 80 which receives a pin 82 which is pivoted to the operating lever 22 at 84. The linkage 68 is provided with a slot 86 which receives a pin 88 which is pivoted to the operating lever 20 at 90. The linkage 68 is provided with a slot 92 which receives a pin 94 which is pivoted to the body 18 at 96. The linkage 68 is provided with a slot 98 which receives a pin 100 which is pivoted to the body 18 at 102. The linkage 68 is provided with a slot 104 which receives a pin 106 which is pivoted to the body 18 at 108. The linkage 68 is provided with a slot 112 which receives a pin 114 which is pivoted to the body 18 at 116. The linkage 68 is provided with a slot 120 which receives a pin 122 which is pivoted to the body 18 at 124. The linkage 68 is provided with a slot 128 which receives a pin 130 which is pivoted to the body 18 at 132. The linkage 68 is provided with a slot 136 which receives a pin 138 which is pivoted to the body 18 at 140. The linkage 68 is provided with a slot 144 which receives a pin 146 which is pivoted to the body 18 at 150. The linkage 68 is provided with a slot 152 which receives a pin 154 which is pivoted to the body 18 at 156. The linkage 68 is provided with a slot 160 which receives a pin 162 which is pivoted to the body 18 at 164. The linkage 68 is provided with a slot 168 which receives a pin 170 which is pivoted to the body 18 at 174. The linkage 68 is provided with a slot 176 which receives a pin 178 which is pivoted to the body 18 at 184. The linkage 68 is provided with a slot 186 which receives a pin 188 which is pivoted to the body 18 at 196. The linkage 68 is provided with a slot 192 which receives a pin 194 which is pivoted to the body 18 at 204. The linkage 68 is provided with a slot 208 which receives a pin 210 which is pivoted to the body 18 at 224. The linkage 68 is provided with a slot 220 which receives a pin 222 which is pivoted to the body 18 at 236. The linkage 68 is provided with a slot 236 which receives a pin 238 which is pivoted to the body 18 at 256. The linkage 68 is provided with a slot 252 which receives a pin 254 which is pivoted to the body 18 at 274. The linkage 68 is provided with a slot 276 which receives a pin 278 which is pivoted to the body 18 at 296. The linkage 68 is provided with a slot 292 which receives a pin 294 which is pivoted to the body 18 at 314. The linkage 68 is provided with a slot 316 which receives a pin 318 which is pivoted to the body 18 at 336. The linkage 68 is provided with a slot 332 which receives a pin 334 which is pivoted to the body 18 at 356. The linkage 68 is provided with a slot 352 which receives a pin 354 which is pivoted to the body 18 at 374. The linkage 68 is provided with a slot 376 which receives a pin 378 which is pivoted to the body 18 at 396. The linkage 68 is provided with a slot 392 which receives a pin 394 which is pivoted to the body 18 at 414. The linkage 68 is provided with a slot 416 which receives a pin 418 which is pivoted to the body 18 at 436. The linkage 68 is provided with a slot 432 which receives a pin 434 which is pivoted to the body 18 at 456. The linkage 68 is provided with a slot 452 which receives a pin 454 which is pivoted to the body 18 at 474. The linkage 68 is provided with a slot 476 which receives a pin 478 which is pivoted to the body 18 at 496. The linkage 68 is provided with a slot 492 which receives a pin 494 which is pivoted to the body 18 at 514. The linkage 68 is provided with a slot 516 which receives a pin 518 which is pivoted to the body 18 at 536. The linkage 68 is provided with a slot 532 which receives a pin 534 which is pivoted to the body 18 at 556. The linkage 68 is provided with a slot 552 which receives a pin 554 which is pivoted to the body 18 at 574. The linkage 68 is provided with a slot 576 which receives a pin 578 which is pivoted to the body 18 at 596. The linkage 68 is provided with a slot 592 which receives a pin 594 which is pivoted to the body 18 at 614. The linkage 68 is provided with a slot 616 which receives a pin 618 which is pivoted to the body 18 at 636. The linkage 68 is provided with a slot 632 which receives a pin 634 which is pivoted to the body 18 at 656. The linkage 68 is provided with a slot 652 which receives a pin 654 which is pivoted to the body 18 at 674. The linkage 68 is provided with a slot 676 which receives a pin 678 which is pivoted to the body 18 at 696. The linkage 68 is provided with a slot 692 which receives a pin 694 which is pivoted to the body 18 at 714. The linkage 68 is provided with a slot 716 which receives a pin 718 which is pivoted to the body 18 at 736. The linkage 68 is provided with a slot 732 which receives a pin 734 which is pivoted to the body 18 at 756. The linkage 68 is provided with a slot 752 which receives a pin 754 which is pivoted to the body 18 at 774. The linkage 68 is provided with a slot 776 which receives a pin 778 which is pivoted to the body 18 at 796. The linkage 68 is provided with a slot 792 which receives a pin 794 which is pivoted to the body 18 at 814. The linkage 68 is provided with a slot 816 which receives a pin 818 which is pivoted to the body 18 at 836. The linkage 68 is provided with a slot 832 which receives a pin 834 which is pivoted to the body 18 at 856. The linkage 68 is provided with a slot 852 which receives a pin 854 which is pivoted to the body 18 at 874. The linkage 68 is provided with a slot 876 which receives a pin 878 which is pivoted to the body 18 at 896. The linkage 68 is provided with a slot 892 which receives a pin 894 which is pivoted to the body 18 at 914. The linkage 68 is provided with a slot 916 which receives a pin 918 which is pivoted to the body 18 at 936. The linkage 68 is provided with a slot 932 which receives a pin 934 which is pivoted to the body 18 at 956. The linkage 68 is provided with a slot 952 which receives a pin 954 which is pivoted to the body 18 at 974. The linkage 68 is provided with a slot 976 which receives a pin 978 which is pivoted to the body 18 at 996. The linkage 68 is provided with a slot 992 which receives a pin 994 which is pivoted to the body 18 at 1014. The linkage 68 is provided with a slot 1016 which receives a pin 1018 which is pivoted to the body 18 at 1036. The linkage 68 is provided with a slot 1032 which receives a pin 1034 which is pivoted to the body 18 at 1056. The linkage 68 is provided with a slot 1052 which receives a pin 1054 which is pivoted to the body 18 at 1074. The linkage 68 is provided with a slot 1076 which receives a pin 1078 which is pivoted to the body 18 at 1096. The linkage 68 is provided with a slot 1092 which receives a pin 1094 which is pivoted to the body 18 at 1114. The linkage 68 is provided with a slot 1116 which receives a pin 1118 which is pivoted to the body 18 at 1136. The linkage 68 is provided with a slot 1132 which receives a pin 1134 which is pivoted to the body 18 at 1156. The linkage 68 is provided with a slot 1152 which receives a pin 1154 which is pivoted to the body 18 at 1174. The linkage 68 is provided with a slot 1176 which receives a pin 1178 which is pivoted to the body 18 at 1196. The linkage 68 is provided with a slot 1192 which receives a pin 1194 which is pivoted to the body 18 at 1214. The linkage 68 is provided with a slot 1216 which receives a pin 1218 which is pivoted to the body 18 at 1236. The linkage 68 is provided with a slot 1232 which receives a pin 1234 which is pivoted to the body 18 at 1256. The linkage 68 is provided with a slot 1252 which receives a pin 1254 which is pivoted to the body 18 at 1274. The linkage 68 is provided with a slot 1276 which receives a pin 1278 which is pivoted to the body 18 at 1296. The linkage 68 is provided with a slot 1292 which receives a pin 1294 which is pivoted to the body 18 at 1314. The linkage 68 is provided with a slot 1316 which receives a pin 1318 which is pivoted to the body 18 at 1336. The linkage 68 is provided with a slot 1332 which receives a pin 1334 which is pivoted to the body 18 at 1356. The linkage 68 is provided with a slot 1352 which receives a pin 1354 which is pivoted to the body 18 at 1374. The linkage 68 is provided with a slot 1376 which receives a pin 1378 which is pivoted to the body 18 at 1396. The linkage 68 is provided with a slot 1392 which receives a pin 1394 which is pivoted to the body 18 at 1414. The linkage 68 is provided with a slot 1416 which receives a pin 1418 which is pivoted to the body 18 at 1436. The linkage 68 is provided with a slot 1432 which receives a pin 1434 which is pivoted to the body 18 at 1456. The linkage 68 is provided with a slot 1452 which receives a pin 1454 which is pivoted to the body 18 at 1474. The linkage 68 is provided with a slot 1476 which receives a pin 1478 which is pivoted to the body 18 at 1496. The linkage 68 is provided with a slot 1492 which receives a pin 1494 which is pivoted to the body 18 at 1514. The linkage 68 is provided with a slot 1516 which receives a pin 1518 which is pivoted to the body 18 at 1536. The linkage 68 is provided with a slot 1532 which receives a pin 1534 which is pivoted to the body 18 at 1556. The linkage 68 is provided with a slot 1552 which receives a pin 1554 which is pivoted to the body 18 at 1574. The linkage 68 is provided with a slot 1576 which receives a pin 1578 which is pivoted to the body 18 at 1596. The linkage 68 is provided with a slot 1592 which receives a pin 1594 which is pivoted to the body 18 at 1614. The linkage 68 is provided with a slot 1616 which receives a pin 1618 which is pivoted to the body 18 at 1636. The linkage 68 is provided with a slot 1632 which receives a pin 1634 which is pivoted to the body 18 at 1656. The linkage 68 is provided with a slot 1652 which receives a pin 1654 which is pivoted to the body 18 at 1674. The linkage 68 is provided with a slot 1676 which receives a pin 1678 which is pivoted to the body 18 at 1696. The linkage 68 is provided with a slot 1692 which receives a pin 1694 which is pivoted to the body 18 at 1714. The linkage 68 is provided with a slot 1716 which receives a pin 1718 which is pivoted to the body 18 at 1736. The linkage 68 is provided with a slot 1732 which receives a pin 1734 which is pivoted to the body 18 at 1756. The linkage 68 is provided with a slot 1752 which receives a pin 1754 which is pivoted to the body 18 at 1774. The linkage 68 is provided with a slot 1776 which receives a pin 1778 which is pivoted to the body 18 at 1796. The linkage 68 is provided with a slot 1792 which receives a pin 1794 which is pivoted to the body 18 at 1814. The linkage 68 is provided with a slot 1816 which receives a pin 1818 which is pivoted to the body 18 at 1836. The linkage 68 is provided with a slot 1832 which receives a pin 1834 which is pivoted to the body 18 at 1856. The linkage 68 is provided with a slot 1852 which receives a pin 1854 which is pivoted to the body 18 at 1874. The linkage 68 is provided with a slot 1876 which receives a pin 1878 which is pivoted to the body 18 at 1896. The linkage 68 is provided with a slot 1892 which receives a pin 1894 which is pivoted to the body 18 at 1914. The linkage 68 is provided with a slot 1916 which receives a pin 1918 which is pivoted to the body 18 at 1936. The linkage 68 is provided with a slot 1932 which receives a pin 1934 which is pivoted to the body 18 at 1956. The linkage 68 is provided with a slot 1952 which receives a pin 1954 which is pivoted to the body 18 at 1974. The linkage 68 is provided with a slot 1976 which receives a pin 1978 which is pivoted to the body 18 at 1996. The linkage 68 is provided with a slot 1992 which receives a pin 1994 which is pivoted to the body 18 at 2014. The linkage 68 is provided with a slot 2016 which receives a pin 2018 which is pivoted to the body 18 at 2036. The linkage 68 is provided with a slot 2032 which receives a pin 2034 which is pivoted to the body 18 at 2056. The linkage 68 is provided with a slot 2052 which receives a pin 2054 which is pivoted to the body 18 at 2074. The linkage 68 is provided with a slot 2076 which receives a pin 2078 which is pivoted to the body 18 at 2096. The linkage 68 is provided with a slot 2092 which receives a pin 2094 which is pivoted to the body 18 at 2114. The linkage 68 is provided with a slot 2116 which receives a pin 2118 which is pivoted to the body 18 at 2136. The linkage 68 is provided with a slot 2132 which receives a pin 2134 which is pivoted to the body 18 at 2156. The linkage 68 is provided with a slot 2152 which receives a pin 2154 which is pivoted to the body 18 at 2174. The linkage 68 is provided with a slot 2176 which receives a pin 2178 which is pivoted to the body 18 at 2196. The linkage 68 is provided with a slot 2192 which receives a pin 2194 which is pivoted to the body 18 at 2214. The linkage 68 is provided with a slot 2216 which receives a pin 2218 which is pivoted to the body 18 at 2236. The linkage 68 is provided with a slot 2232 which receives a pin 2234 which is pivoted to the body 18 at 2256. The linkage 68 is provided with a slot 2252 which receives a pin 2254 which is pivoted to the body 18 at 2274. The linkage 68 is provided with a slot 2276 which receives a pin 2278 which is pivoted to the body 18 at 2296. The linkage 68 is provided with a slot 2292 which receives a pin 2294 which is pivoted to the body 18 at 2314. The linkage 68 is provided with a slot 2316 which receives a pin 2318 which is pivoted to the body 18 at 2336. The linkage 68 is provided with a slot 2332 which receives a pin 2334 which is pivoted to the body 18 at 2356. The linkage 68 is provided with a slot 2352 which receives a pin 2354 which is pivoted to the body 18 at 2374. The linkage 68 is provided with a slot 2376 which receives a pin 2378 which is pivoted to the body 18 at 2396. The linkage 68 is provided with a slot 2392 which receives a pin 2394 which is pivoted to the body 18 at 2414. The linkage 68 is provided with a slot 2416 which receives a pin 2418 which is pivoted to the body 18 at 2436. The linkage 68 is provided with a slot 2432 which receives a pin 2434 which is pivoted to the body 18 at 2456. The linkage 68 is provided with a slot 2452 which receives a pin 2454 which is pivoted to the body 18 at 2474. The linkage 68 is provided with a slot 2476 which receives a pin 2478 which is pivoted to the body 18 at 2496. The linkage 68 is provided with a slot 2492 which receives a pin 2494 which is pivoted to the body 18 at 2514. The linkage 68 is provided with a slot 2516 which receives a pin 2518 which is pivoted to the body 18 at 2536. The linkage 68 is provided with a slot 2532 which receives a pin 2534 which is pivoted to the body 18 at 2556. The linkage 68 is provided with a slot 2552 which receives a pin 2554 which is pivoted to the body 18 at 2574. The linkage 68 is provided with a slot 2576 which receives a pin 2578 which is pivoted to the body 18 at 2596. The linkage 68 is provided with a slot 2592 which receives a pin 2594 which is pivoted to the body 18 at 2614. The linkage 68 is provided with a slot 2616 which receives a pin 2618 which is pivoted to the body 18 at 2636. The linkage 68 is provided with a slot 2632 which receives a pin 2634 which is pivoted to the body 18 at 2656. The linkage 68 is provided with a slot 2652 which receives a pin 2654 which is pivoted to the body 18 at 2674. The linkage 68 is provided with a slot 2676 which receives a pin 2678 which is pivoted to the body 18 at 2696. The linkage 68 is provided with a slot 2692 which receives a pin 2694 which is pivoted to the body 18 at 2714. The linkage 68 is provided with a slot 2716 which receives a pin 2718 which is pivoted to the body 18 at 2736. The linkage 68 is provided with a slot 2732 which receives a pin 2734 which is pivoted to the body 18 at 2756. The linkage 68 is provided with a slot 2752 which receives a pin 2754 which is pivoted to the body 18 at 2774. The linkage 68 is provided with a slot 2776 which receives a pin 2778 which is pivoted to the body 18 at 2796. The linkage 68 is provided with a slot 2792 which receives a pin 2794 which is pivoted to the body 18 at 2814. The linkage 68 is provided with a slot 2816 which receives a pin 2818 which is pivoted to the body 18 at 2836. The linkage 68 is provided with a slot 2832 which receives a pin 2834 which is pivoted to the body 18 at 2856. The linkage 68 is provided with a slot 2852 which receives a pin 2854 which is pivoted to the body 18 at 2874. The linkage 68 is provided with a slot 2876 which receives a pin 2878 which is pivoted to the body 18 at 2896. The linkage 68 is provided with a slot 2892 which receives a pin 2894 which is pivoted to the body 18 at 2914. The linkage 68 is provided with a slot 2916 which receives a pin 2918 which is pivoted to the body 18 at 2936. The linkage 68 is provided with a slot 2932 which receives a pin 2934 which is pivoted to the body 18 at 2956. The linkage 68 is provided with a slot 2952 which receives a pin 2954 which is pivoted to the body 18 at 2974. The linkage 68 is provided with a slot 2976 which receives a pin 2978 which is pivoted to the body 18 at 2996. The linkage 68 is provided with a slot 2992 which receives a pin 2994 which is pivoted to the body 18 at 3014. The linkage 68 is provided with a slot 3016 which receives a pin 3018 which is pivoted to the body 18 at 3036. The linkage 68 is provided with a slot 3032 which receives a pin 3034 which is pivoted to the body 18 at 3056. The linkage 68 is provided with a slot 3052 which receives a pin 3054 which is pivoted to the body 18 at 3074. The linkage 68 is provided with a slot 3076 which receives a pin 3078 which is pivoted to the body 18 at 3096. The linkage 68 is provided with a slot 3092 which receives a pin 3094 which is pivoted to the body 18 at 3114. The linkage 68 is provided with a slot 3116 which receives a pin 3118 which is pivoted to the body 18 at 3136. The linkage 68 is provided with a slot 3132 which receives a pin 3134 which is pivoted to the body 18 at 3156. The linkage 68 is provided with a slot 3152 which receives a pin 3154 which is pivoted to the body 18 at 3174. The linkage 68 is provided with a slot 3176 which receives a pin 3178 which is pivoted to the body 18 at 3196. The linkage 68 is provided with a slot 3192 which receives a pin 3194 which is pivoted to the body 18 at 3214. The linkage 68 is provided with a slot 3216 which receives a pin 3218 which is pivoted to the body 18 at 3236. The linkage 68 is provided with a slot 3232 which receives a pin 3234 which is pivoted to the body 18 at 3256. The linkage 68 is provided with a slot 3252 which receives a pin 3254 which is pivoted to the body 18 at 3274. The linkage 68 is provided with a slot 3276 which receives a pin 3278 which is pivoted to the body 18 at 3296. The linkage 68 is provided with a slot 3292 which receives a pin 3294 which is pivoted to the body 18 at 3314. The linkage 68 is provided with a slot 3316 which receives a pin 3318 which is pivoted to the body 18 at 3336. The linkage 68 is provided with a slot 3332 which receives a pin 3334 which is pivoted to the body 18 at 3356. The linkage 68 is provided with a slot 3352 which receives a pin 3354 which is pivoted to the body 18 at 3374. The linkage 68 is provided with a slot 3376 which receives a pin 3378 which is pivoted to the body 18 at 3396. The linkage 68 is provided with a slot 3392 which receives a pin 3394 which is pivoted to the body 18 at 3414. The linkage 68 is provided with a slot 3416 which receives a pin 3418 which is pivoted to the body 18 at 3436. The linkage 68 is provided with a slot 3432 which receives a pin 3434 which is pivoted to the body 18 at 3456. The linkage 68 is provided with a slot 3452 which receives a pin 3454 which is pivoted to the body 18 at 3474. The linkage 68 is provided with a slot 3476 which receives a pin 3478 which is pivoted to the body 18 at 3496. The linkage 68 is provided with a slot 3492 which receives a pin 3494 which is pivoted to the body 18 at 3514. The linkage 68 is provided with a slot 3516 which receives a pin 3518 which is pivoted to the body 18 at 3536. The linkage 68 is provided with a slot 3532 which receives a pin 3534 which is pivoted to the body 18 at 3556. The linkage 68 is provided with a slot 3552 which receives a pin 3554 which is pivoted to the body 18 at 3574. The linkage 68 is provided with a slot 3576 which receives a pin 3578 which is pivoted to the body 18 at 3596. The linkage 68 is provided with a slot 3592 which receives a pin 3594 which is pivoted to the body 18 at 3614. The linkage 68 is provided with a slot 3616 which receives a pin 3618 which is pivoted to the body 18 at 3636. The linkage 68 is provided with a slot 3632 which receives a pin 3634 which is pivoted to the body 18 at 3656. The linkage 68 is provided with a slot 3652 which receives a pin 3654 which is pivoted to the body 18 at 3674. The linkage 68 is provided with a slot 3676 which receives a pin 3678 which is pivoted to the body 18 at 3696. The linkage 68 is provided with a slot 3692 which receives a pin 3694 which is pivoted to the body 18 at 3714. The linkage 68 is provided with a slot 3716 which receives a pin 3718 which is pivoted to the body 18 at 3736. The linkage 68 is provided with a slot 3732 which receives a pin 3734 which is pivoted to the body 18 at 3756. The linkage 68 is provided with a slot 3752 which receives a pin 3754 which is pivoted to the body 18 at 3774. The linkage 68 is provided with a slot 3776 which receives a pin 3778 which is pivoted to the body 18 at 3796. The linkage 68 is provided with a slot 3792 which receives a pin 3794 which is pivoted to the body 18 at 3814. The linkage 68 is provided with a slot 3816 which receives a pin 3818 which is pivoted to the body 18 at 3836. The linkage 68 is provided with a slot 3832 which receives a pin 3834 which is pivoted to the body 18 at 3856. The linkage 68 is provided with a slot 3852 which receives a pin 3854 which is pivoted to the body 18 at 3874. The linkage 68 is provided with a slot 3876 which receives a pin 3878 which is pivoted to the body 18 at 3896. The linkage 68 is provided with a slot 3892 which receives a pin 3894 which is pivoted to the body 18 at 3914. The linkage 68 is provided with a slot 3916 which receives a pin 3918 which is pivoted to the body 18 at 3936. The linkage 68 is provided with a slot 3932 which receives a pin 3934 which is pivoted to the body 18 at 3956. The linkage 68 is provided with a slot 3952 which receives a pin 3954 which is pivoted to the body 18 at 3974. The linkage 68 is provided with a slot 3976 which receives a pin 3978 which is pivoted to the body 18 at 3996. The linkage 68 is provided with a slot 3992 which receives a pin 3994 which is pivoted to the body 18 at 4014. The linkage 68 is provided with a slot 4016 which receives a pin 4018 which is pivoted to the body 18 at 4036. The linkage 68 is provided with a slot 4032 which receives a pin 4034 which is pivoted to the body 18 at 4056. The linkage 68 is provided with a slot 4052 which receives a pin 4054 which is pivoted to the body 18 at 4074. The linkage 68 is provided with a slot 4076 which receives a pin 4078 which is pivoted to the body 18 at 4096. The linkage 68 is provided with a slot 4092 which receives a pin 4094 which is pivoted to the body 18 at 4114. The linkage 68 is provided with a slot 4116 which receives a pin 4118 which is pivoted to the body 18 at 4136. The linkage 68 is provided with a slot 4132 which receives a pin 4134 which is pivoted to the body 18 at 4156. The linkage 68 is provided with a slot 4152 which receives a pin 4154 which is pivoted to the body 18 at 4174. The linkage 68 is provided with a slot 4176 which receives a pin 4178 which is pivoted to the body 18 at 4196. The linkage 68 is provided with a slot 4192 which receives a pin 4194 which is pivoted to the body 18 at 4214. The linkage 68 is provided with a slot 4216 which receives a pin 4218 which is pivoted to the body 18 at 4236. The linkage 68 is provided with a slot 4232 which receives a pin 4234 which is pivoted to the body 18 at 4256. The linkage 68 is provided with a slot 4252 which receives a pin 4254 which is pivoted to the body 18 at 4274. The linkage 68 is provided with a slot 4276 which receives a pin 4278 which is pivoted to the body 18 at 4296. The linkage 68 is provided with a slot 4292 which receives a pin 4294 which is pivoted to the body 18 at 4314. The linkage 68 is provided with a slot 4316 which receives a pin 4318 which is pivoted to the body 18 at 4336. The linkage 68 is provided with a slot 4332 which receives a pin 4334 which is pivoted to the body 18 at 4356. The linkage 68 is provided with a slot 4352 which receives a pin 4354 which is pivoted to the body 18 at 4374. The linkage 68 is provided with a slot 4376 which receives a pin 4378 which is pivoted to the body 18 at 4396. The linkage 68 is provided with a slot 4392 which receives a pin 4394 which is pivoted to the body 18 at 4414. The linkage 68 is provided with a slot 4416 which receives a pin 4418 which is pivoted to the body 18 at 4436. The linkage 68 is provided with

tive main spools 30 and 32 to the right of center only.

One of the spools such as 30 is provided with grooving 66 for cooperation with a spring pressed detent 68 to retain the spool in any of its three positions. The detent may be released by admission of pressure fluid through a conduit 70.

Referring now to FIG. 1, the base 10 includes a pilot operated valve 72 for regulating the delivery of pressure fluid from the pump 12 to the poppet valve body are block 18. The valve 72 slides in a bore 74 and seats upon a seat 76 to close off communication between delivery passage 33 and a chamber 78 which is open to the reservoir through exhaust passage 79. The poppet valve 72 has an orifice 80 through which inlet pressure is admitted to the inner cylindrical chamber 73 of the valve 72 to act on the upwardly facing or closing area of the poppet valve 72 and with the assistance of a spring 82, normally urges the poppet toward its seat 76. In the position of the parts illustrated in FIG. 1, however, the closing area is vented through ports 75 in the cylindrical wall of valve 72 passages 84, 86, 88 and 90 and the grooves 87, 89 of the spools. Orifice 80 creates sufficient pressure drop to such flow that the poppet valve is held open by the full inlet pressure acting on its lower or opening face thereby allowing fluid to pass by the seat 76 and into the chamber 78. When either of the spools are moved from the position shown in FIG. 1, the flow of fluid through the passages 84, 86, 88, 90 is cut off. When the flow of fluid through orifice 80 is cut off, the poppet 72 is seated by the spring 82.

A pressure responsive pilot valve 92 is slidable in a fixed ferrule 94 mounted in the bore 74 and held in place by a cap 96. A spring 98 allows the pilot relief valve 92 to move upwardly when a predetermined pressure is reached in the bore 74 and will first allow fluid to escape through the valve orifice 93 in the plate 95 and the radial passages 99 in the ferrule 94 into a chamber 100 which connects by passages such as illustrated at 102 in FIGS. 1 and 3 with the passage 70 and the detent 68 a valve 25. At a still higher pressure in bore 74, the pilot valve 92 will rise sufficiently to allow fluid to escape through the exhaust passage 104 and thus poppet 72 will act as a pressure limiting relief valve under these conditions.

Referring now to FIG. 4, the meter-out valve, which is associated with the spool 30 of valve 25, is illustrated there in larger scale and exemplifies the meter-out valves associated with each of the other three spools. The piston 55 and spring 57 is shown in FIG. 2 is an alternate form used in all the spools. The poppet 58 has a fairly large orifice 106 extending through it to allow fluid to act on its closing surface to hold poppet 58 closed. The poppet 58 slides in a bore 108 formed in the body 18. Passages 110 around the cylindrical portion 18a bypasses the opening formed by the bore 108 from the seat 44 to the outlet port 34. A smaller seat 112 is formed at the end of inner bore 108 and faces oppositely to the seat 44, being normally closed by the conical portion 112 the pilot valve 62. The latter has wings 114 which guide it within the interior bore 116 of the poppet 58 and provide an abutment for the spring 118 which urges both the main poppet 58 and the pilot valve 62 against their respective seats.

The pilot valve 62 has a restricting pin 120 which is spaced from the orifice 106 sufficiently as to not begin restricting it until the pilot valve 62 has moved to open the seat 112 to its maximum opening. At about this po-

sition in the travel of pilot valve 62, the restricting pin approaches the orifice 106 and when the flow therethrough is sufficiently restricted compared with the available flow area at the seat 112, the poppet 58 will rapidly move to the left into the cylindrical portion 18a, further restricting the orifice 106 and providing free flow from the motor port 40 to the outlet port 34 through passages 110. Prior to this, all such flow took place through orifice 106 and the orifice formed by seat 112. The area of the latter, of course, is governed by the taper on the pilot valve 62 and the degree of its displacement as main spool 30 is moved to the right.

The valve system here disclosed allows very gradual metering out of fluid from the cylinder port along a substantial range of travel of the main spool as previously described. During such travel, pressure is maintained in the opposite cylinder port and in the inlet port because of the wider opening between ports 31 and 48 or 50. This pressure reacts upon the pilot relief valve 92 which opens to admit pressure fluid through passages 102 and 70 to the detent 68 and thus assures that precise control of the valve spools is not inhibited by the detent.

It is frequently desirable in the control of double acting cylinders which are subject always to a gravity load in one direction that means be provided for preventing the load from dropping under gravity alone faster than the rate of pressure fluid supply from the pump will fill the unloaded end of the cylinder. Customarily, a separate counterbalance valve is provided which blocks the outflow from the loaded end of the cylinder until a predetermined substantial pressure is built up in the pressure supply line. The present valve system is readily adaptable to performing this function by the provision of a small auxiliary piston within the spools.

This alternative feature is illustrated in FIG. 2, in connection with lower spool 32. The spool has a bore 51 at its right-hand end which communicates by a passage 53 with the pressure supply port 31. Slidable in the bore 51 is a piston 55 which is urged to the right by a spring 57, which spring is weaker than the spring 122 for the pilot valve 64. Thus, when the valve spools are shifted to lower the load by exhausting fluid from port 40, the pilot valve 64 cannot be opened by piston 55 and spring 57 alone. It requires, in addition, the development of a substantial pressure level in the supply port 31 to hold piston 55 in the position illustrated and thus overcome the force of spring 122 and open pilot valve 64. In this way, the sudden dropping of a heavy load is prevented with less pressure is supplied from port 31. The load must be positively lowered by a significant positive pressure applied in the lowering direction.

I claim:

1. A hydraulic directional valve system comprising a body having a pair of spool-receiving bores, each with lateral ports for inlet and for outlet, with an axial port for flow to and from a motor and with a third lateral port connected by a one-way passage with the axial port; pair of main spools slidable in the bores to control flow between the lateral ports, operating means to shift the spools simultaneously in opposite directions, a seat in each axial port, a poppet coaxial with each spool and biased toward the seat by a spring and by pressure in the axial port, and means controlled by the main spool for moving the poppet in a direction opposite to motion of the main spool.

2. A valve system as defined in claim 1 wherein the last means includes a pilot valve controlling the pressure balance of the poppet valve.

3. A valve system as defined in claim 2 wherein the poppet valve includes an orifice therethrough and a pilot valve controlled by the main spool for restricting the orifice to unbalance the poppet.

4. A hydraulic directional valve system comprising a body having a pair of spool-receiving bores, each with a lateral port for inlet and for outlet, with an axial port for flow to and from a motor and with a third lateral port connected by a one-way passage with the axial port, a pair of main spools slidable in the bores to control flow between the lateral ports, operating means to shift the spools simultaneously in opposite directions, a seat in each axial port, a poppet coaxial with each spool and biased toward the seat by a spring and by pressure in the axial port, an oppositely facing smaller seat between each spool and its poppet, and a pilot

valve normally closing the smaller seat and arranged to be progressively opened by motion of the main spool for metered flow out of the axial port and means on the pilot valve for rapidly opening the poppet after a further increment of motion of the main spool.

5. A valve system as defined in claim 4 wherein the poppet has an axial orifice larger than the maximum orifice between the pilot valve and the smaller seat, and the pilot valve includes a pin for restricting the orifice in the poppet upon said further increment of motion of the main spool.

6. A valve system as defined in claim 5 wherein a common spring biases both the poppet and the pilot valve toward the large and small seats respectively.

7. A valve system as defined in claim 1 wherein the last means is rendered ineffective until a substantial pressure is built up in the inlet port thereby to prevent motor over-run under the action of gravity.
